(57) **CLAIM**

The ornamental design for an abdominal exerciser with rotatable seat, as shown and described.

DESCRIPTION

FIG. 1 is a front, right perspective view of an abdominal exerciser with rotatable seat showing our new design;

FIG. 2 is a front, right perspective view thereof, shown from a higher angle;

FIG. 3 is a front, right perspective view thereof, shown with the seat in a rotated position;

FIG. 4 is a rear, left perspective view thereof;

FIG. 5 is a front perspective view thereof;

FIG. 6 is a right side perspective view thereof;

FIG. 7 is a left side perspective view thereof;

FIG. 8 is a rear perspective view thereof;

FIG. 9 is a top plan view thereof; and,

FIG. 10 is a front, right perspective view thereof, shown with the seat in a further rotated position.

The broken lines illustrate portions of the abdominal exerciser with rotatable seat which form no part of the claimed design.
